UNITED STATES PATENT OFFICE.

ALFRED P. SLOAN, JR., OF NEW YORK, N. Y.

DESIGN FOR A FRAME FOR SHAFTING-HANGERS.

SPECIFICATION forming part of Design No. 32,340, dated March 13, 1900.

Application filed October 19, 1899. Serial No. 734,141. Term of patent 14 years.

To all whom it may concern:

Be it known that I, ALFRED P. SLOAN, Jr., a citizen of the United States, residing at No. 240 Garfield Place, New York, (Brooklyn,) 5 county of Kings, State of New York, have invented a certain new and useful Design for Frames for Shafting-Hangers, fully described and represented in the following specification and the accompanying drawings, forming a part of the same.

The design is illustrated in the annexed drawings, in which--

Figure 1 is a plan of the top of the hanger-frame. Fig. 2 is a side elevation, and Fig. 3, 15 an edge view, of the same. Fig. 4 is a section on line 4 4 in Fig. 2. Fig. 5 shows the bottom end of the frame, and Fig. 6 is a cross-section on line 6 6 in Fig. 3.

The hanger-frame is provided with the 20 usual outwardly-curved legs *a* and foot-plate *b*, and the distinguishing feature of the design is the rectangular opening *c* in the lower part of the frame, with recessed slots extending through the four bars surrounding such 25 opening.

a' a' are the side bars, having vertical slots

f, each provided upon the inner side with the longitudinal recess *f'*.

d designates the bottom cross-bar, formed with the longitudinal slot *g*, provided upon 30 the inner side with the longitudinal recess *g'*. The upper cross-bar *e* is similarly provided with the longitudinal slot *h*, having upon the inner side the longitudinal recess *h'*.

My design includes the vertical slots *f*, provided each with the longitudinal recess *f'* 35 and the longitudinal slots *g* and *h*, provided, respectively, with the longitudinal recesses *g'* and *h'*.

Having thus described my design, what I 40 claim as new, and desire to secure by Letters Patent, is--

The design for frame for shafting-hanger, substantially as herein shown and described.

In testimony whereof I have hereunto set 45 my hand in the presence of two subscribing witnesses.

ALFRED P. SLOAN, JR.
